UNITED STATES PATENT OFFICE.

FREDERICK W. ROBERTSHAW, OF PITTSBURGH, PENNSYLVANIA, ASSIGNOR TO ROBERTSHAW THERMOSTAT COMPANY, OF YOUNGWOOD, PENNSYLVANIA, A CORPORATION OF PENNSYLVANIA.

THERMOSTAT.

Application filed July 24, 1923. Serial No. 653,407.

To all whom it may concern:

Be it known that I, FREDERICK W. ROBERTSHAW, a citizen of the United States, residing at Pittsburgh, county of Allegheny, and 5 State of Pennsylvania, have invented a new and useful Improvement in Thermostats, of which the following is a full, clear, and exact description.

The present invention relates broadly to 10 thermostats, and more particularly to thermostats of the character adapted to be used in connection with valves, such as gas valves, to provide combinations suitable for use with ovens, although it will be apparent that 15 its use in this respect is not limited.

The construction herein illustrated may be of the general character shown in Patent No. 1,455,663 of May 15, 1923, issued jointly to George A. Robertshaw and myself, but 20 is adapted to provide improved means for preventing any leakage between the valve chamber and the body of the thermostat, and also to assist in maintaining the parts in the desired adjusted position.

25 It will be understood that the embodiment of the invention shown in the accompanying drawings is for purposes of illustration only, as changes may obviously be made in the construction and operation disclosed 30 without departing from the spirit of my invention or scope of my broader claims.

In the drawings:

Figure 1 is a longitudinal sectional view 35 through the valve and its operating thermostat, certain of the parts being broken away and certain of the parts being shown in elevation; and

Figure 2 is a view similar to Figure 1, but on an enlarged scale, illustrating in detail 40 certain of the features of construction.

In the form of invention illustrated, there is provided a supporting body 2 which may be in the form of a valve casing having a suitable inlet connection 3 and an outlet connection 4, these parts constituting a portion of one form of controlling device. Intermediate the ports of these connections the casing may be provided with a seat 5 adapted to cooperate with a valve 6, for cutting off communication between the ports. The valve is normally urged in the direction of 45 the seat by suitable means such as a spring 7.

For accurately guiding the valve during its opening and closing movements, it may

be formed with a stem 8 extending into a 55 boss 9 projecting inwardly from the casing. Access to the casing for inspection or renewal of parts is permitted by removing a closure 10, it being apparent that the closure is removable at will without disturbing the 60 setting of any other parts of the combination. The usual bypass, as customary in the art, and as clearly shown in the patent referred to, may be utilized.

Extending rearwardly from the supporting body or valve casing is a projection 11 having a threaded outer surface. This thread, which may be either single or double, is preferably of comparatively steep pitch. 65 Cooperatively threaded thereon is a revolving couple or adapter 12 having one end provided with an internal thread corresponding to the threads on the projection 11, and having its opposite end internally threaded with a thread of different pitch, for example a 70 standard thread, adapted to receive the threaded end 13 of an expanding element 14.

Within the expandable member is a non-expandable member 15 of suitable material 75 abutting against a packing pin 16 separate from, and in alignment with, the valve stem 8. Heretofore considerable difficulty has been encountered in attempting to provide a gas tight joint between the interior of the valve casing and the interior of the 80 member 14. If the pin 16 has been made with a tight enough fit to prevent gas leakage, the efficient operation of the valve, particularly under the action of the spring 7, has been impaired. In accordance with the 85 present invention, this objection is obviated by the provision of an improved packing which may comprise a body of suitable packing 90 17 adapted to be compressed by a packing gland 18. The packing gland in turn is urged longitudinally of the packing pin to 95 compress the packing by means of a spring 19. At its opposite end this spring may abut against the shoulder 20 or the end of the member 14. It will be apparent that this 100 construction maintains a tight seal around the packing pin to prevent any leakage, and that by using a spring of proper scale any binding is prevented.

On the exterior of the casing 2, so as to 105 be visible to a user throughout its entire length, is a plate 21 having suitable graduations thereon indicating different degrees of

temperature at which it may be desired to maintain the oven or other means being controlled. Clamped about the revolving couple 12 is an arm 22 provided with an operating handle 23 and a pointer 24, the latter cooperating with the graduations of the plate 21. By moving the handle 23 it will be apparent that the revolving couple will be rotated, thereby moving the same toward or away from the support or casing 2, by means of the threaded projection 11. This movement is amplified by reason of the high pitch of the threads so as to move the member 14 as may be desired for the required operation of the valve 6.

It has been found that the spring 19 also serves an important function in connection with the couple 12, and the adjustment of the parts. This is true for the reason that the spring maintains a tension on the operating threads, thereby maintaining the handle 23 in the position to which it is moved. This is highly desirable, particularly when used with ovens and the like, as the closing and opening of the oven door does not change the setting.

Certain advantages of the present invention arise from the provision of a revolving couple between a supporting body carrying the member to be actuated and the thermostat, together with means for maintaining the revolving couple in adjusted position.

Still other advantages of the invention arise from the provision of improved packing means preventing the leakage of any gas from the chamber of the valve being actuated into the interior of the thermostat and thence to the oven or the like.

I claim:

1. The combination with a thermostat and a valve for actuation thereby, of separate threaded controlling means between the valve and thermostat, and means cooperating with said controlling means for preventing leak-

age from the valve into the thermostat and for maintaining a load on said threads, substantially as described.

2. The combination with a thermostat and a valve for actuation thereby, of operating means between the valve and thermostat, comprising a threaded couple and a pin, and a spring-pressed packing cooperating with both of said means to prevent leakage around the pin and past the threads of such couple, substantially as described.

3. A thermostat, comprising a supporting body, a member movably mounted thereon, a heat responsive device for actuating said member, an adjustable revolving couple connecting said member and device, and means for maintaining said couple in adjusted position, substantially as described.

4. In a thermostat, a valve, a thermostatic element, an operating pin between said valve and element and separate therefrom, and means for packing said pin, said means also tending to maintain the thermostat in adjusted position, substantially as described.

5. In a thermostat, a valve, a thermostatic element, an adjustable revolving couple connecting said valve and element for adjusting the thermostat, and means within said couple for preventing leakage between said valve and thermostat and tending to maintain the thermostat in adjusted position, substantially as described.

6. In a thermostat, a valve, a thermostatic element, a revolving couple connecting said valve and element and movable for adjusting the thermostat, and spring pressed packing within said couple for preventing leakage between said valve and thermostat and maintaining a load on said couple, substantially as described.

In testimony whereof I have hereunto set my hand.

FREDERICK W. ROBERTSHAW.
